RODMILL

Original Filed Dec. 29, 1941

UNITED STATES PATENT OFFICE

2,394,453

ROD MILL

Kálmán Z. Huszár, Cincinnati, Ohio

Original application December 29, 1941, Serial No. 424,839. Divided and this application November 13, 1944, Serial No. 563,241

2 Claims. (Cl. 241—171)

This invention relates to a rodmill for crushing, pulverizing or mixing materials, such as dye, face powder, or the like, and is a division of my co-pending application, Serial No. 424,839, filed December 29, 1941, for Rodmill, now Patent Number 2,367,585, dated January 16, 1945.

An object of this invention is to provide in a pulverizing mill an improved means whereby the ground material may be selectively discharged therefrom during the rotation of the mill.

Another object of this invention is to provide in a pulverizing mill of this kind, an improved means whereby the ground material may be removed from an end of the mill and retained in a chamber at one end of the mill for rotation with the mill and subsequently discharged from the collecting chamber as the mill rotates.

To the foregoing objects, and others which may hereinafter more fully appear, the invention consists of the novel construction, combination and arrangement of parts, as will be more specifically referred to and illustrated in the accompanying drawing, but it is to be understood that changes, variations, and modifications may be resorted to which fall within the scope of the invention as claimed.

In the drawing:

Figure 1 is a detail side elevation partly in longitudinal section of a pulverizing mill constructed according to an embodiment of this invention.

Figure 2 is a fragmentary vertical section of the closure operator.

Figure 3 is an end view of the mill, omitting the frame structure, the carriage and tracks, to show the radially disposed housings.

Referring to the drawing, the numeral 10 designates generally a pulverizing mill member which is rotatably supported on a base structure 11. The mill member 10 includes a cylindrical body 12 containing a number of pulverizing units or bars 13. The cylindrical body 12 is formed with an opening 14 through which the material is charged for filling the mill. The closure member 15 is adapted to be removably secured to the cylindrical wall 12 for closing the filling opening 14.

A forward end wall 16 is secured to one end of the cylindrical body 12 and a rear end wall 17 is secured to the opposite end of the cylindrical wall 12. A trunnion 18 is secured to the end wall 16 and is rotatably supported in a bearing 19 carried by an upstanding bearing support 20 which is fixed to the base 11 and braced by means of one or more bracing members 21. The cylindrical body 12 adjacent the end wall 17 thereof has

secured to the outer peripheral surface thereof a circular track or rail 22, which engages a pair of spaced apart rollers 23 carried by bearing members 24 which are fixed to the base 11.

5 A ring gear 25 is fixed to the outer side of the end wall 16 and is adapted to mesh with a driving pinion 26 carried by a shaft 27. The shaft 27 is connected to a reduction gearing 28 of conventional construction which has connected therewith a driving wheel 29. The driving wheel 29 may be operated in any suitable manner from a power member (not shown).

The end wall 17 has secured thereto a pair of diametrically opposed and outwardly extending or offset housings 30 and 31. The housing 30 is formed of an outer side wall 32 and opposite end walls 33, thereby forming a pulverizing material receiving chamber 34. The outer end of the housing 30 has an outer end wall 35 which is connected with the walls 33 and with the wall 32, and is outwardly offset from the outer marginal edge of the end wall 17. An inwardly extending wall 36 is connected at one end to the forward end of the outer wall 35, and at the outer end is fixed to the peripheral surface of the cylindrical body 12 forwardly of the end wall 17.

The cylindrical wall or body 12 is formed with an opening 37 communicating with the passage 38 formed by the wall 36, so that when the housing 30 is in a lowermost position, the pulverized material will flow downwardly through the opening 37 and the passage 38 into the lower portion of the housing 30. The inner portion of the housing 30 is connected to the inner portion of the housing 31 by means of an annular connecting wall 39 which, as shown in Figure 1, is inwardly offset from the outer walls of the two housings 30 and 31.

30 40 The housing 31 is similar in every detail to the construction of the housing 30, the cylindrical wall 12 being formed with a discharge opening 40 adjacent the end wall 17 which communicates with the chamber 41 through a passage 42 similar to the passage 38.

45 50 A conical material guiding member generally designated as 92 is disposed coaxial with the openings 45 and 91, and is fixedly mounted on a stub shaft 93. The stub shaft 93 is fixed in a central boss 94 carried by a plurality of radially disposed bars 95 which are removably fixed to the outer side of the end wall 17. A frusto-conical guide member 96 is fixed at its base to the outer side of the end wall 17, and loosely engages about the base or inner end of the conical guide member 92. The fixed guide member 96 is

adapted to prevent the pulverizing material from returning to the mill 10 in the space between the base of the conical guide member 92 and the rear side of the end wall 17. The conical guide member 92 is formed with a centrally disposed sleeve 97 engaging about the stub shaft 93, and a nut or other fastening device 98 is mounted on the rear end of the stub shaft 93 and bears against the rear end of the sleeve 97, so as to tightly hold the guide member 92 relative to the mill 10.

A cylindrical member 99 is disposed within the opening 91 and is formed with an annular and right angularly disposed flange 100 bearing against the outer side of the annulus 39, which is fixed relative to the rear sides of the housings 30 and 31. A plurality of radially disposed and inwardly extending webs 101 are fixed to the cylindrical member 99 and are also fixed to the outer surface of the conical guide member 92, so as to provide an additional supporting means for the guide member 92.

A material delivery spout or nozzle 102 is disposed in downwardly inclined position with respect to the mill 10 and is formed at its upper end portion with an annular flange 103 bearing against an annular gasket or sealing member 104 which is interposed between the flange 100 and the flange 103. The spout or nozzle 102 is fixed to a frame structure 104^b forming part of a carriage 105. The carriage 105 is horizontally movable on tracks 106 supported in any suitable manner rearwardly of the mill 10. The carriage 105 includes rollers 107 engaging the tracks 106, so that the nozzle 102 may be shifted away from the rear end of the mill 10.

A valve plate 108 of the disc-like form is adapted to selectively engage against the outer end of the cylindrical member 99, so as to close the passage formed in the annulus 99, and prevent the material from the housings 30 and 31 from being discharged into the nozzle 102. The valve plate 108 is carried by a horizontally disposed and endwise movable shaft 109, which is slidably mounted in a bearing 110 carried by the frame 104^b and is slideable through a boss 111 fixed to the nozzle 102. The shaft 109 as shown in Figure 1 is provided at its inner end with a head or flange 112 about which a flanged collar 113 loosely engages. The collar 113 is formed with an annular groove 114 within which the outer end portion of a valve supporting spring 115 is mounted.

The forward or inner end of the spring 115 is extended through an opening 116 formed in the plate 108, and is bent laterally as at 117 on the inner side of the plate 108, so that the inner end of the spring 115 will be fixedly disposed with respect to the plate 108. The spring 115 provides a flexible coupling or connection between the valve member 108 and the operating shaft 109, whereas the flanged collar 113 provides a swivelled connection between the spring 115 and the shaft 109. In order to provide a means whereby the valve member 108 may be angularly shifted at the same time that it is moved outwardly and away from the sleeve or annulus 99, I have provided a depending lug or abutment 118 which is fixed to the upper portion of the nozzle 102.

When the shaft 109 is moved rearwardly, the upper end of the plate 108 will strike the abutment 118, thereby holding the upper end of the plate 108 against further rearward movement, whereas continued rearward movement of the shaft 109 will cause the plate 108 to be angularly disposed with respect to the vertical as shown in

full lines. In this angular position the material from the housings 30 and 31 will be discharged therefrom into the delivery nozzle 102.

The shaft 109 is adapted to be moved endwise by means of a pivoted lever 119 which is pivotally mounted as at 100 on a rearwardly extending bracket or arm 121 carried by the frame structure 104. The arm or lever 119 is formed with an elongated slot 122 therein within which a pin 123 fixed relative to the shaft 109 loosely engages.

In the operation of this mill, the body 10 is rotated through the reduction gearing 28 and gears 26 and 25. Initially lever 119 is moved forwardly to the dotted line position shown in Figure 1, so as to hold closure 108 against the outer end of cylindrical member 99. In this position of closure 108 the material which enters the collecting housings 30 and 31 through openings 37 and 40, respectively, will be retained in these housings. At any predetermined time closure 108 may be moved outwardly to the full line position in Figure 1, whereupon the material which is pulverized and positioned in housings 30 and 31 will be discharged into spout 102 by conical member 92. In the event it is desired to return the initially pulverized material to the mill, carriage 105 is moved along track 106 so as to withdraw discharge member and spout 102 from the adjacent end of the mill and a reversely disposed conical member, as embodied in my co-pending application, Serial No. 563,242, filed as of even date herewith, may be inserted in opening 91.

What I claim is:

1. In combination a pulverizing mill including 35 a rotatable body formed with a cylindrical side wall and opposite end walls, a pair of radially disposed housings carried by one of said end walls, each housing comprising a rear wall and opposite side walls fixed to said one end wall, said cylindrical wall having opposed openings, passage forming means fixed to said housings and extending outwardly therefrom, said passage forming means communicating with said housings and encompassing said openings, means forming an 40 annular valve seat between the adjacent ends of said rear walls, said one end wall having an axial opening, a conical material guide member disposed axially of said axial opening, radially disposed and outwardly directed webs fixed to said 45 guide member, a cylindrical guide supporting member fixed to the outer ends of said webs and engaging in said valve seat, a tubular member fixed axially of said guide member and extending inwardly thereof, a stub shaft disposed in said 50 tubular member, a right angularly disposed supporting bar fixed to said shaft, said bar having cutouts at the opposite ends thereof for engagement in said axial opening to thereby support said bar diametrically of said opening, means securing 55 said guide member on said stub shaft a valve plate 55 adapted to engage with said annular valve seat, a valve plate supporting and operating shaft, means movably supporting said shaft, means supporting 60 said valve plate from said shaft, and a nozzle 65 encompassing said valve plate and extending downwardly therefrom.

2. In combination a pulverizing mill including 70 a rotatable body formed with a cylindrical side wall and opposite end walls, a pair of radially disposed housings carried by one of said end walls, each housing comprising a rear wall and opposite side walls fixed to said one end wall, said cylindrical wall having opposed openings, passage forming means fixed to said housings and extending 75 outwardly therefrom, said passage forming

means communicating with said housings and encompassing said opening, means forming an annular valve seat between the adjacent ends of said rear walls, said one end wall having an axial opening a conical material guide member disposed axially of said axial opening, radially disposed and outwardly directed webs fixed to said guide member, a cylindrical guide supporting member fixed to the outer ends of said webs and engaging in said valve seat, a tubular member fixed axially of said guide member and extending inwardly thereof, a stub shaft disposed in said tubular member, a right angularly disposed supporting bar fixed to said shaft, said bar having cutouts at the opposite ends thereof for engagement in said axial opening to thereby support said bar dia-

metrically of said opening, means securing said guide member on said stub shaft, a valve plate adapted to engage with said annular valve seat, a valve plate supporting and operating shaft, 5 means movably supporting said shaft, means supporting said valve plate from said shaft, a nozzle encompassing said valve plate, and extending downwardly therefrom, an abutment carried by said nozzle engageable with the top of said valve plate upon movement of said valve plate to an open position, said valve plate supporting means including means whereby said valve plate may shift angularly with respect to said supporting shaft upon endwise movement of said shaft outwardly of said nozzle.

KÁLMÁN Z. HUSZÁR.
